SPOTTING APPARATUS

John F. Fink, Arlington, Va.

Application February 13, 1947, Serial No. 728,362

10 Claims. (Cl. 68—5)

1

The invention relates to improvements in spotting apparatus as employed in the cleaning industry.

In accordance with the present practice cleaning operations are generally performed upon a so-called spotting board which is ordinarily hollow and provided with a perforated top. The spotting board is usually equipped with a supply pipe for steam or other pressure fluid connected by means of a flexible hose or the like to a so-called spotting gun which is accessible to the operator at the spotting board, and is equipped with a wooden or other insulated handle which is grasped by the operator, who uses the gun for directing steam or other pressure fluid upon the goods upon the spotting board. The flow of pressure fluid to the spotting gun is generally controlled by a pedal-actuated valve, the pedal being associated with the spotting board and accessible to the foot of the operator. Cleaning fluids, such as liquid soap, chemical cleaning fluids, water or the like, are generally supplied from separate sources so that the operator must lay down the spotting gun and separately apply the cleaning fluid.

Various means have been proposed for remedying this defect so that both the cleaning and pressure fluids may be applied through a single nozzle. In one such device the cleaning fluid is supplied to the pressure fluid line at a point far removed from the spotting gun. In such case the line becomes filled with the cleaning fluid and when it is desired to apply steam alone it requires a considerable amount of time before the line has cleared of the cleaning fluid and clean steam or other pressure fluid emerges from the nozzle of the spotting gun.

Other devices intended for the same general purpose have proved unsatisfactory from the commercial standpoint and have not generally replaced the old practice of applying cleaning fluid and pressure fluid through separate instrumentalities.

The primary object of the present invention is accordingly to provide improved means for selectively applying pressure fluid alone or pressure fluid and cleaning fluid together, or for applying the cleaning fluid alone, in which device the disadvantages attendant upon previous attempts to supply pressure fluid and cleaning fluid through the same pipe line and/or nozzle are overcome.

The invention will be more readily understood by reference to the accompanying drawings and the following detailed description, in which are set forth illustrative embodiments of the invention.

2

In the drawings:

Fig. 1 is a side elevation of the combined apparatus including the improved spotting gun;

Fig. 2 is a longitudinal section through the spotting gun;

Fig. 3 is a section on the line 3—3 of Fig. 2; and

Fig. 4 is a bottom plan view of the nozzle.

Referring in detail to the drawings, reference letter A denotes a spotting board, which may be of conventional form and which is ordinarily equipped with a steam supply line B having a control valve C actuated by means of a treadle D accessible to the foot of the operator. The steam supply line B is connected through a flexible tube E with a spotting gun G which is accessible to the hand of the operator, and which in the present device includes various improvements characterizing the invention.

20 The spotting gun G comprises a two-part wooden handle 10 split longitudinally and releasably held together with resilient spring rings 11, 11 fitting in grooves 12, one at each end of the wooden handle. The wooden handle 10 is recessed at each end 13 to fit over spacing collars 14, 14 which are suitably secured as by welding, soldering or the like, to a pair of metal tubes 15 and 16, the one being connected to the pressure line E and the other being connected to a flexible tube 17 through which cleaning fluid is received from a suitable source of supply 18 preferably elevated above the level of the spotting board.

25 The pipes 15 and 16 within the wooden handle 10 are preferably insulated from each other by coverings of asbestos or the like 19 to prevent undue heating and consequent vaporizing of the cleaning fluid, with resulting back pressure through the line 17 to the supply tank 18, which is preferably connected through a siphon 20 to the line 17. A flexible sleeve 21 of rubber or the like may be slipped over the wooden handle 10 after the parts are assembled. While the handle 10 is preferably of wood, other suitable insulating material may be employed, as, for example, various synthetics such as plastics or the like.

30 The pipes 15 and 16 carrying the pressure fluid and cleaning fluid, respectively, lead to the spotting nozzle G. This nozzle comprises an outer casing 25 to which the ends of both tubes 15 and 16 are secured as by welding, soldering or the like. The nozzle G includes an outer chamber 26 with which the pressure fluid line 15 communicates, and an inner chamber or passageway 50 27 through which cleaning fluid may be supplied through the line 16. The casing 25 is closed at

the top by means of a cap 28 threaded thereon. The passage 27 is controlled by reciprocating valve member 29 having an operating handle 30 pivoted at 31 to the top of the valve, and pivoted at 32 to a link 33 which in turn is pivotally mounted between the pipes 15 and 16 intermediate the wooden handle 10 and the nozzle G. A spring 34 tends to hold the valve 29 normally closed. A thumbpiece 35 projects rearwardly from the valve handle 30 over the wooden spotting handle 10 so as to be readily accessible to the operator grasping the handle 10, leaving his other hand free at all times. In operation pressure fluid may be supplied through the nozzle G and chamber 26 surrounding the inner passage 27 and through an elongated space 40 surrounding an elongated mouth portion 41 of the inner tube 27.

To supply cleaning fluid as well as pressure fluid the operator presses upon the thumbpiece 35 while grasping the handle 10, thereby opening the valve 29 while at the same time stepping upon the treadle D to supply pressure fluid through the outer space 26, thereby creating a vacuum which draws cleaning fluid to the nozzle G from the source 18 through siphon 20, line 17, pipe 16 and inner tube 27. After flow through the line 17 has commenced the cleaning fluid may then be supplied by gravity alone from the elevated supply tank 18 without supplying pressure fluid at the same time. This operation is often desirable when a small amount of liquid cleaning fluid is needed without the simultaneous application of pressure.

The invention has been described in detail for the purpose of illustration, but it will be apparent that numerous modifications and variations may be resorted to without departing from the spirit of the invention in its broadest aspects. For example, while steam is ordinarily preferred as the pressure fluid for some purposes compressed air, either heated or not, may be employed either in addition to the steam or as a substitute therefor. Moreover, while liquid soap is ordinarily the preferred cleaning fluid other cleaning fluids may be substituted in whole or in part, and even water may be employed in some instances. Other modifications and variations will suggest themselves to those skilled in the art.

I claim:

1. In a cleaning system, including a spotting board equipped with a pedal-controlled valved pressure fluid line leading to a spotting gun for supplying heated pressure fluid thereto, the improvement wherein the spotting gun includes an insulating handle enclosing a pair of separate pipes, one communicating with the hot pressure fluid line, and the other communicating with a source of cleaning fluid, and a nozzle portion beyond and spaced from the handle portion and including an outer passage communicating directly with the fluid pressure pipe at all times and an inner passage connected with the cleaning fluid pipe line; valve means within the gun for controlling said inner passage independent of the pressure fluid, and valve actuating means therefor including a thumbpiece accessible to the hand of the operator while grasping said insulating handle.

2. A cleaning system as set forth in claim 1, wherein the nozzle outlet of said outer passage surrounds the outlet of the inner passage, whereby when both fluid lines are opened the pressure

fluid serves to draw the cleaning fluid through the inner passage to initiate its flow.

3. A system as set forth in claim 2, wherein the cleaning fluid supplied through the axial passage of the nozzle is liquid, and the source thereof is elevated above the spotting board and is connected to the spotting gun through a siphon and a flexible hose portion, whereby after the flow of cleaning fluid is initiated by the flow of pressure fluid from the nozzle, said liquid cleaning fluid will continue to flow by gravity independent of the pressure fluid.

4. In a cleaning system, a pressure supply line, pedal means controlling said pressure supply line, a source of cleaning fluid, a spotting gun including an elongated insulating handle having spaced pipes extending therethrough each communicating at one end with a spotting nozzle, and connected at the other end with the pedal-controlled pressure supply line and with the source of cleaning fluid, respectively, said nozzle including an outer passage freely communicating with the pipe connected to the pressure supply line, a valved inner passage communicating with the pipe connected with the source of cleaning fluid, and valve means controlling said inner passage and having an operating member provided with a thumbpiece accessible to the hand of an operator while grasping said insulating handle.

5. In a cleaning system, a pressure supply line for hot pressure fluid, pedal means controlling said line, a source of liquid cleaning fluid, a spotting gun including an elongated insulating handle having spaced pipes extending therethrough each communicating at one end with a spotting nozzle, and connected at the other end with the pedal-controlled pressure supply line and with the source of cleaning fluid, respectively, said nozzle including an outer passage freely communicating with the pipe connected to the hot pressure fluid supply line, and an inner passage communicating with the pipe connected with the source of liquid cleaning fluid, and valve means controlling said inner passage and having a pivoted operating member provided with a thumbpiece accessible to the hand of an operator while grasping said insulating handle.

6. In a cleaning system, in combination with a spotting board, a spotting gun, a fluid pressure line communicating with the gun and including a flexible hose portion adjacent the gun, and pedal controlled valve means for said fluid pressure line remote from the gun but accessible to the foot of an operator at said spotting board; the improvement wherein a cleaning fluid line communicates with the gun for supplying cleaning fluid thereto independent of the fluid pressure line, said cleaning fluid line also including a flexible hose portion and valve means at the gun accessible to the hand of an operator holding the gun for controlling the flow of cleaning fluid to the spotting board.

7. In a cleaning system, including a spotting gun, a spotting board equipped with a pressure fluid line leading to the spotting gun, and pedal actuated valve means accessible to the foot of an operator at the spotting board for controlling the fluid pressure line; the improvement wherein the spotting gun comprises an insulating handle enclosing a pair of separate pipes both connected to flexible hose to permit free movement of the spotting gun, one connected to the pressure fluid line and the other communicating with a source of cleaning fluid, said gun including a mixing nozzle having an axial passage connected with

the cleaning fluid pipe line, an outer passage surrounding the axial passage and freely communicating with the pedal controlled pressure fluid line, valve means controlling the axial cleaning fluid passage and valve actuating means therefor including a thumbpiece accessible to the hand of the operator while grasping the insulating handle, thereby permitting the operator to supply pressure fluid, cleaning fluid, or both, to the spotting board from a single spotting gun while leaving one hand of the operator free.

8. In a cleaning system, a spotting board, a spotting gun for use in connection therewith, a line for supplying hot pressure fluid, including a flexible hose portion communicating with the gun, and pedal controlled valve means remote from the gun but accessible to the foot of an operator at said spotting board for controlling said pressure fluid through said line, a separate source of liquid cleaning fluid located at a level above the level of the spotting board, and a line connecting said source with said spotting gun, including a siphon adjacent the source to prevent premature flow of liquid cleaning fluid, and a flexible hose portion connected to said gun, said gun comprising a heat insulating handle enclosing a pair of separate pipes, one pipe connected to one of said flexible hose portions and the other pipe connected to the other of said flexible hose portions, said gun also including a mixing and discharge nozzle adjacent the handle and having an axial passage connected to the cleaning fluid supply line, an outer passage surrounding the axial passage and freely communicating with the pedal controlled pressure fluid supply line, valve means controlling said axial cleaning fluid passage, and valve actuating means therefor including a thumbpiece accessible to the hand of the operator while grasping the insulating handle, the outlet for said pressure fluid surrounding the outlet for said liquid cleaning fluid whereby on initially operating the pedal and thumbpiece the pressure fluid serves to draw liquid cleaning fluid from said elevated supply source past said siphon, after which the cleaning fluid may be supplied by gravity alone.

9. A spotting gun including an elongated separable two-part insulating handle portion, separate steam and cleaning liquid supply lines passing longitudinally through the handle and connected at one end with a source of steam and of cleaning liquid, respectively, a mixing nozzle communicating with the other ends of said supply lines and adapted to supply fluid to articles to be cleaned, and solid heat insulating means independent of the handle separating the steam supply line and the cleaning liquid line within

the handle to prevent undue heating and consequent vaporization of the cleaning liquid by contact with the steam supply line, valve means in said nozzle controlling the flow of cleaning fluid therethrough, operating means for said valve means, accessible to the hand of an operator while grasping said handle, and remote pedal actuated valve means for controlling the steam supply pipe line.

10. A spotting gun including a heat insulating handle portion, separate steam and moisture supply lines passing through the insulating handle and connected at one end with a source of steam and of cleaning fluid, respectively, said supply lines each including a flexible hose portion leading to the handle, pedal controlled means for the steam supply line located at a position accessible to the foot of an operator but remote from the handle portion, a mixing nozzle communicating with the supply lines at the opposite end of the handle from the hose portions and adapted to supply fluid to articles to be cleaned, and valve means associated with said mixing nozzle accessible to the hand of an operator grasping the handle for controlling the cleaning fluid supply therethrough.
